Karl Viertel

UNITED STATES PATENT OFFICE.

JAKOB ZEITTER, OF LORCH, GERMANY.

WATER TOWER FOR FIRE-FIGHTING PURPOSES.

Application filed January 22, 1926, Serial No. 83,077, and in Germany May 10, 1924.

My invention relates to improvements in water discharge devices for fire extinguishing purposes and more particularly to so-called water towers, comprising a water 5 delivery pipe with a jet nozzle at its upper end, the latter being adapted to throw a powerful jet of water of great volume and force over a large fire area.

One of the objects of my invention is to 10 simplify the construction of the whole device and to facilitate the operation of the mechanism for controlling the direction of the discharge.

Another object sought to be attained by 15 my invention is to thus design the water tower, that it can be erected to a comparatively great height, and at the same time to enable the operator to accurately and positively control from an easily accessible place 20 without delay and danger the discharge from the nozzle, viz, to play the stream in the direction of any radius of a globe around the top end of the delivery pipe.

Another object of my invention is to thus 25 design and construct a water tower of the character set forth that it is in all its parts safe against destruction and getting out of order through fire and adverse climatic conditions, and that fire hoses and like members 30 of rubber, hemp or other materials, capable of deterioration and of becoming sharply bent over, are, thoroly eliminated.

The nature of my invention is briefly outlined 35 in the annexed claim and will be more fully understood from the following specification, taken together with the accompanying drawing in which

Fig. 1 is a broken view in elevation partly in section of the improved water tower.

Fig. 2 shows the lower end of the water 40 tower.

Fig. 3 is a side view of its upper end.

As seen in Figs. 1 and 2, the water tower 45 consists of a couple of water delivery pipes a , a_1 , forming the main structure of the tower and being adapted to be connected at their base with any available source of water under compression.

Altho Fig. 2 indicates that the water 50 tower is supplied from a fixed water main pipe viz, on land, my invention may equally well be employed on fire fighting boats, trucks, wheeled ladders or other conveyances.

The delivery pipes a , a_1 are connected 55

with a water chamber d , which is formed at its top end with a stuffing box b for the rotatable discharge pipe e and with another stuffing box c at its bottom for a spindle e_1 , the latter being rigidly attached to the discharge pipe, and by which the latter can be swung around its axis. 60

The spindle e_1 is operated by means of an internal gear wheel f , pinion g and connecting rod s , the latter being provided at the bottom end with a worm gear h , h_1 . 65

By turning the worm wheel h_1 the operator can rotate the discharge pipe e around its axis to any desired position.

The discharge pipe e is preferably formed 70 at its base with elongated slots or perforations t , representing inlet passages for the water; the arrangement of perforations in rotatable pipes of the character under consideration being known per se in the art. 75

As seen in Fig. 3 the discharge pipe e carries a bifurcated section e_2 . To the upper end of the latter the nozzle member proper k is attached preferably by means of stuffing boxes i , i_1 , and is adapted to be 80 swung about its horizontal axis by means of a swing arm m . Said arm m is pivotally attached at its lower end to a sleeve member n , which is slidably guided on the discharge pipe e , as seen in Figs. 1 and 3. 85

The sleeve n can be shifted up and down by means of a screw spindle q and a nut p threaded thereon. Spindle q can be rotated through a hand wheel r .

The nut is cooperatively connected with 90 the sleeve n by a pair of rods o , o_1 , substantially vertically extending alongside the pipes a and e .

By turning the hand wheel r which is 95 preferably located near the worm gear h , h_1 , so as to be in easy reach of the operator, the latter can swing the nozzle k around its horizontal axis as indicated in dotted lines in Fig. 1 and he can at the same time turn the delivery pipe e around its vertical axis into any position required. 100

As outlined above, my invention lends itself to a variety of applications in cases where a particularly large fire area must be kept under control from an easily accessible and safe place. 105

I am aware that so-called water towers for fire fighting purposes are known per se in the art and that minor structural details as e. g. worm gears, levers, screw spindles, 110

etc., have already been used for turning the pipe section and nozzle section of water towers.

It is obvious to those skilled in the art that various changes in the size, shape, proportion and minor details of construction may be resorted to without departing from the spirit and the leading ideas of my invention.

10 What I claim as new in my invention and desire to protect by Letters Patent is:

In a water tower, service pipes, a water chamber into which said pipes lead, a discharge pipe having its lower end opening into the water chamber, means for supporting the discharge pipe to permit its rotation relative to the service pipes, a spindle se-

cured to the discharge pipe within the water chamber, manually operable means arranged below the water chamber for rotating the spindle and thereby the discharge pipe, a nozzle carried by the upper end of the discharge pipe and mounted for swinging about a horizontal axis, a sleeve slidably mounted on the discharge pipe and connected to the nozzle, and manually operable means arranged below the water chamber for moving the sleeve vertically of the discharge pipe and thereby adjusting the nozzle on its horizontal axis.

20 25 30 In testimony whereof I have signed my name to this specification.

JAKOB ZEITTER.
